UNITED STATES PATENT OFFICE.

FREDERICK M. SIMONS, OF BOWLING GREEN, PENNSYLVANIA, ASSIGNOR TO SIMONS BROS. COMPANY, A CORPORATION OF PENNSYLVANIA.

DISPLAY TRAY.

Application filed May 27, 1925. Serial No. 33,082.

The object of my invention is to provide a construction of display tray suitable for thimbles and other articles, the designs of which are to be displayed, and which tray shall support the articles whereby a general or perspective view of them is presented to the eye and, at the same time, different sizes of each of the articles are also simultaneously presented to view by means of the same display tray; and moreover, whereby the tray is provided with display pictures of the articles with the name or number or other designation by which the articles may be readily distinguished, said pictures in alinement with the supporting means for the corresponding displayed articles.

My object is also to provide the tray with a plurality of transverse rows of inclined supporting pockets arranged side by side in each row, each of the pockets of one row arranged in alinement with corresponding pockets of each of the other rows, and means arranged transversely of the tray having thereon in alinement with each of the pockets marks to indicate differences in size of the articles to be supported by the inclined pockets; and in which further, the tray is provided with one or more removable strips having prints thereon illustrating the articles which are to be displayed in the pockets, said prints respectively in alinement with the transverse rows of pockets.

My invention also includes other features of construction which, together with those above enumerated, are fully described hereinafter and pointed out in the claims.

Referring to the drawings: Fig. 1 is a plan view of a display tray embodying my improvements; Fig. 2 is a side view of the same, with part in section, taken on line 2—2 of Fig. 1; Fig. 3 is an enlarged view of the left hand end of Fig. 2 and taken on line 3—3 of Figs. 1 and 4; Fig. 4 is a vertical sectional view on the same scale as Fig. 3 and taken on line 4—4 of Figs. 1 and 3; and Fig. 5 is a perspective view of a portion of one of the wooden forms for providing the inclined pockets.

2 is a shallow box shaped receptacle having a closed bottom 3 and open top to form a tray. At each side of the contained space is a block 4 having a depth very slightly less than the vertical depth of the tray space, said blocks arranged fore and aft, as it were, and forming lateral wall abutments for the

transverse rows of pockets to be herein-after described. Each of these blocks are provided with side plates 5 of angle form, the upper flanges of said plates arranged horizontally and directed toward each other to provide undergrooved parts 6 arranged at a distance apart to provide a channel 8 above the floor 7 on the upper surfaces of the blocks 4. In this manner there is provided a grooved channel above each block 65 in which a printed card 18 and transparent sheet strip 19 over it are removably positioned, the purpose of which will be described hereinafter. The ends of the channels are open for the insertion or removal 70 of the cards and transparent strips, but the upwardly projecting edges of the sides 2 of the tray prevent them from dropping out of the groove unintentionally. To provide a finish to the plates 5, they may be covered 75 with thin leather or velvet indicated at 16 in Fig. 3.

The tray, intermediate of the blocks 4, 4, is provided with a plurality of transverse rows of pockets 10 for receiving and supporting the thimbles or articles on display as indicated in dotted lines in the lower 80 left hand part of Fig. 1 and in Figs. 2, 3 and 4. These pockets 10 are formed in strips of wood 9 (Figs. 2 and 5) in which 85 the grooves for forming the pockets are inclined as shown in Figs. 4 and 5. A plurality of these strips are arranged in parallel relation transversely of the tray and separated by upright division boards 13 90 forming vertical sides transverse to the lengths of the grooves and against which the thimbles rest when positioned in the pockets, (Fig. 4). It will be seen that these pockets of each row are in alinement with 95 corresponding pockets with each other row, separated only by the division boards 13 aforesaid, and each pocket of a row receives a thimble of a definite size. To designate the size of the article, a transverse block 14 100 is arranged above or parallel to the rows of pockets and has upon its surface 15 symbols or indicia in alinement with the pockets 10 to indicate the "size" of the article and in the case of thimbles I have indicated the sizes as #7 to #11 inclusive, or five sizes. 105

The grooved blocks 9 also may have their upper surfaces covered with velvet or other soft material, as indicated 12, to prevent 110

scratching or abrasion of the articles resting in the pockets or grooves.

As shown in Figs. 1 and 2, there is a vertical division 11 midway of the length of the tray, thereby dividing the pockets into two sets each set having the surface 15 similarly numbered as to sizes, as it will be noted that the numbers seven to eleven are repeated. From this it will be understood that the tray shown is really a double tray and each half of the tray is provided with its display strip 18, but, for convenience in symmetry, the printed card and its retaining groove devices are arranged respectively at the left and right of the two sections of the tray. Of course, if there were more than five sizes of the articles displayed, then the size numbers would be extended, and if there were ten sizes, then the tray, as shown in Fig. 1, would be complete if the right hand display card and its supporting groove devices were omitted. I, therefore, do not limit myself to the number of pockets which are to be contained either transversely for the different sizes nor for the display of different styles of the articles, as the tray may be designed to display more or less than the five designs shown.

Referring more particularly to the cards 18, there is printed thereon in alinement with each one of the transverse rows of pockets a picture or illustration of the article which is to be displayed in the corresponding row, and said illustration may have a number or a name, as indicated in Fig. 1, by which the said article is known in the trade. A purchaser, wishing to purchase one of the thimbles, for example, would designate by the number or name the particular thimble desired and the salesman would examine the printed card to find which row contained the thimbles called for. The purchaser would then designate the size required and that particular thimble would be selected from the pocket in which it rests. In this manner, one complete set of sizes of the thimbles of each design shown on the card would be displayed in the tray, and upon making a sale, the vacancy thus left would be filled with another thimble of the design and size required. In this manner, there are a limited number of thimbles to be handled by the salesman in connection with the sale of these goods to the public.

In the case of silver thimbles, there is more or less tendency for the same to darken from sulphur in the air and, aside from this, it is desirable that the articles shall be kept covered, except when on actual display, and to protect them I provide a soft pad 17 indicated in Figs. 3 and 4, said pad being large enough to substantially fill the space in the tray between the blocks 4, 4, so that it covers all of the thimbles or other articles which may be supported in the pockets.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having thus described my invention, what I claim and desire to secure by Letters Patent is:

1. A display tray having a plurality of transverse parallel rows of pockets and the pockets of each row in respective alinement with the corresponding pockets of the other rows, and in which further, the tray is provided at one side with a fixed grooved channel at right angles to the transverse rows of pockets and at one of its sides parallel to the transverse rows of pockets with means in vertical alinement with the corresponding pockets of the several transverse rows for indicating the size of the article to be displayed in the respective pockets, combined with a removable card arranged in and of substantially the length of the grooved channel having prints thereon illustrating the different designs of articles to be displayed in the respective transverse rows of pockets and the several prints arranged in alinement with said respective rows, the said grooved channel and printed card being arranged at right angles to the alinement of the means for indicating the sizes of the articles displayed.

2. The invention according to claim 1, wherein further, the side portions of the tray extend above the pocket structures, and the size indicating means and to the level of the grooved channel to provide a rectangular depression adapted for receiving a removable pad.

3. A display tray having arranged within the boundaries of its sides a plurality of grooved transverse rows of pockets in parallel relation and the adjacent strips separated by division strips, characterized by the transverse rows of pockets being formed of separate strips of wood each having its bottom and two upright sides along its length arranged at right angles to each other and its upper surface formed by a plurality of inclined parallel grooves each extending entirely across the strip and of substantially the same cross section throughout its length, the open ends of said grooves of the strip being closed by the division strips.

In testimony of which invention, I hereunto set my hand.

FREDERICK M. SIMONS.
